CLAIM

The ornamental design for a miter saw, as shown and described.

DESCRIPTION

FIG. 1 is a perspective view of a miter saw according to the invention.

FIG. 2 is a front view of the miter saw of FIG. 1.

FIG. 3 is a rear view of the miter saw of FIG. 1.

FIG. 4 is a right side view of the miter saw of FIG. 1; and,

FIG. 5 is a top plan view of the miter saw of FIG. 1.

The broken lines in the drawings depict portions of the miter saw which form no part of the claimed design.
